UNITED STATES PATENT OFFICE.

RANDOLPH N. MARTZ, OF FREDERICK, MARYLAND, ASSIGNOR OF TWO-THIRDS TO SAMUEL D. THOMAS AND MARSHALL FOUT, OF SAME PLACE.

SHUTTER-WORKER.

SPECIFICATION forming part of Letters Patent No. 609,448, dated August 23, 1898.

Application filed January 21, 1898. Serial No. 667,487. (No model.)

To all whom it may concern:

Be it known that I, RANDOLPH N. MARTZ, a citizen of the United States, residing at Frederick, in the county of Frederick and State of Maryland, have invented a new and useful Shutter-Worker, of which the following is a specification.

This invention relates to improvements in shutter-workers of that class which aim to provide means for bowing, opening, or closing the shutter from the inside of a room or apartment, obviating the necessity for opening a window to operate the shutter.

Devices of this class in order to be thoroughly practical and meet the demands of the trade and the public generally should possess the following practical advantages: The device should be readily and easily applied to shutters and windows. It should be capable of application either to right or left hand shutters without impairing the working parts, thus dispensing with separate "rights" and "lefts" for the respective shutters. It should be capable of use with shutters which are hung with different styles of hinges. The joint in the window-sash should be closed practically air and water tight at the point where the operating-rod passes from the inside to the outside of the window. The parts should not be so loosely connected as to be blown open by the wind in stormy weather. The accumulation of sleet and snow on the exposed working parts should not interfere with the free operation of said parts, and the device should be cheap in manufacture and readily assembled for application to a window. My improvement attains these objects in a satisfactory manner; and the invention consists in the peculiar construction and arrangement of parts, which will be hereinafter fully described and claimed.

The accompanying drawings illustrate my improved shutter-worker, in which—

Figure 1 is a perspective view with the shutter in its open position. Fig. 2 is a sectional plan view with the shutter closed. Fig. 3 is a vertical transverse section on the plane indicated by the dotted line 33 of Fig. 2. Fig. 4 is a detail perspective view of the journal and locking-plate. Fig. 5 is a similar view of

the bridged rod-attaching bracket. Fig. 6 is a perspective view of the shaft.

Like numerals of reference denote like and corresponding parts in each of the several figures of the drawings.

In order that others may understand the construction and operation of my shutter-worker, I have illustrated the same in operative relation in the various parts of a window, and by reference to Figs. 1 to 3, inclusive, of 60 the drawings it will be seen that the window-sill is indicated by the numeral 1, the lower sash by 2, the inside sash-strip 3, the shutter 4, and the hinge 5, which connects the shutter to the window-frame. It will be understood that all these parts are ordinary, and that no novelty therefor is claimed in this application.

In carrying my invention into practice I employ a novel construction of bridged attaching-bracket, which is fastened to the shutter 4 at a point close to the hinge 5 thereof. This bracket is constructed to provide for the passage therethrough of rain and snow in inclement weather, thus obviating the settling of water around the screws which fasten the bracket to the shutter and preventing the wood from rotting at the place where the bracket is attached to said shutter. The attaching-bracket consists of an elongated 70 body 7, the three feet 8, which are provided with transverse holes 9, and the extended arm 10, having the round eye 10^a produced therein. The bracket is cast in a single piece of metal or it may be produced in any other 75 suitable way, and said bracket is fastened rigidly to the shutter by ordinary screws, which pass through the holes 9 in the feet 8 thereof. The bracket is designed to afford a means for the attachment of the operating- 80 rod to the shutter, and in this connection it is proper to explain that importance is attached to the employment of the rounded eye 10^a on the bracket, because the eye is adapted to loosely connect with a similar eye on 85 one end of the operating-rod to enable the bracket to be turned to different positions on the rod and thus provide for the use of the bracket interchangeably on right and left hand shutters.

In my shutter-worker I employ a plate 11, that serves a twofold purpose—as a journal for the operating-shaft and as a locking device for the crank-arm, the rod, and the shutter. This plate 11 is cast in a single piece of metal in the semicircular form represented by Fig. 4 of the drawings, and said locking-plate has a hollow boss 12 formed as an integral part thereof. At the straight lower side of the semicircular plate are provided the laterally-extending perforated lugs 13, and the plate is furthermore provided with an arc-shaped series of circular holes or openings 14, which are produced in said plate near its semicircular edge, said series of openings being equidistant from the axial line of the hollow boss 12 of the said plate 11. The semicircular plate is adapted to bear firmly upon the window-sill outside of the lower sash 2 of the window, and the plate is fastened rigidly and firmly in place by means of ordinary screws, which pass through the perforated lugs 13 of the plate. Said plate presents a neat appearance, and as it lies in compact or close relation to the sill it does not interfere with a person leaning out of the window.

15 indicates the operating-shaft, which is fitted loosely in the hollow boss 12 of the journal and locking-plate 11, and this shaft passes through a recess 16 produced in the lower edge of the sash 2 and a similar recess 16^a in the inside of the window-strip 3. The recesses 16 16^a in the sash and window-strip are in the same horizontal plane and in alignment with the boss 12 of the plate 11, and on the inside of the window-frame I employ a looped bearing 26, which is of curved form to snugly embrace the inner part of the shaft 15 to confine said shaft in place on the window-sill. The looped bearing has perforated feet or lugs, through which may be passed ordinary screws to securely fasten said bearing on the window-sill, and from the foregoing description it will be seen that the shaft is 45 journaled securely in the plate 11 and the bearing 26.

The shaft 15 is capable of a semiturning movement in the plate 11, the bearing 26, and the recesses of the sash and window-strip, and 50 in addition to this turning movement the shaft has an endwise movement in said parts for the purpose of freeing the crank-arm from locking engagement with the plate 11. A collar 17 is formed or provided on the shaft 15 at a point intermediate of the length thereof, said collar being either integral with the shaft or rigidly fastened thereto. The collar is positioned on the shaft to abut against the outside of the lower sash 2 over the recess 16 55 therein, and said collar is thus adapted to close said recess practically air and water tight to prevent the entrance of rain and wind into the room through the recess in the sash and window-strip provided for the accommodation 60 of the shaft. The shaft is normally impelled endwise in one direction to hold the crank-arm in locking engagement with the plate 11 by

means of a spring 18. This spring is preferably a coiled spring which loosely encircles the shaft between the collar thereon and the boss 12 of the plate 11, and the ends of said spring are seated against said boss and collar to normally force the shaft inwardly and hold the collar 17 against the outer side of the sash around the recess 16 therein.

75 The outer end of the shaft 15 passes through the boss 12, and to it is fastened rigidly a crank-arm 19, which lies at right angles to the shaft. If desired, the crank-arm may be made as an integral part of the shaft, or said crank-arm may be made separate from the shaft and provided at one end with an opening 20, adapted to receive the shaft, a suitable fastener or key being employed to hold the crank-arm and shaft rigidly together. At 80 its free end the crank-arm 19 is provided with an enlarged rounded eye 21, and at a point intermediate of its length the crank-arm is further provided with a rounded locking-stud 22, adapted to fit in either of the series of apertures 14 in the plate 11. It will be seen that the crank-arm is attached to the shaft 15 to partake of the turning and endwise movements thereof, and thus the crank-arm is adapted to be adjusted by the shaft in its 85 endwise movement to free the locking-stud 22 from engagement with the apertured plate 11; but when the hand-pressure is removed from the shaft 15 the spring 18 reacts and forces the shaft inwardly, thus drawing the 90 crank-arm 19 to a position where its locking-stud 22 will enter one or the other of the apertures in the plate 11.

95 23 designates a connecting-rod between the crank-arm 19 and the attaching-bracket 6. 105 This connecting-rod may be of any desirable length, according to the width of the shutter and the distance of the shaft 15 from the bracket 6, and said rod 23 is provided at its ends with the eyes 24 25, which engage, respectively, with the eye 10^a of the bracket 6 and the eye 21 of the crank-arm 19.

110 I attach importance to the employment of the eye-formed rod loosely connected to the eyes of the crank-arm and the attaching-bracket, because said rod is free to have a sliding or turning movement on said crank-arm and the attaching-bracket, and the parts may readily be turned or reversed to enable the shutter-worker to be applied to either 115 right or left hand shutters. This reversal of the operating parts of the shutter-worker does not involve an inversion of either of said elements, and the described loose connection between said working parts obviates the liability 120 of sleet and snow interfering with the proper movement of one part on the other in stormy weather.

125 The operating-shaft 15 projects inwardly beyond the looped bearing 26, and to said inner end of the shaft is attached or formed an operating-crank 27, the free end of which carries a handpiece 28.

130 The operation may be described briefly as

follows: Assuming that the shutter is closed, the operator first presses the crank 27 and shaft 15 outwardly against the tension of the spring 18, thus releasing the stud 22 of the 5 crank-arm 19 from engagement with the apertured plate 11. The operator while holding the shaft and crank-arm in the described position turns the shaft quickly in one direction, thus throwing the shutter open and 10 past the dead-center of the hinge, and while the shaft is held in the described position, where the locking-stud 22 is free from engagement with the plate, the shaft is turned in the reverse direction, thus throwing the 15 shutter open to its full extent. To close the shutter, the operation described is reversed—that is to say, the shaft is forced outwardly and given a quick turn in one direction to move the shutter past the dead-center, after 20 which the shaft is reversed and the shutter is fully closed. During the operation of opening or closing the shutter the connecting-rod 23 moves freely a limited distance on the crank-arm and the bracket, and when the 25 hand-pressure is removed from the operating shaft the spring moves the shaft inward, thus drawing the arm 19 to a position where its locking-stud 22 will enter one of the apertures in the plate 11.

30 It will be understood that the operating shaft may be turned a limited distance to partly open or close the shutter and that the locking-stud of the arm 19 will engage with the plate 11 to hold the shutter-worker and 35 the shutter in their adjusted positions.

One of the advantages of my improved construction resides in the fact that the operator may by glancing through the window ascertain whether the locking-stud properly 40 engages with an aperture of the plate 11, because the apertures in said plate are visible from the inner side thereof and from the window.

A further advantage resides in arranging 45 the crank-arm 19 and the operating-crank 27 parallel to each other on the shaft 15, so that when the shutter is closed the cranks stand in vertical positions, which gives greater purchase or leverage when the shaft is turned to 50 start the operation of moving the shutter on its hinged connection with the window-frame, and when the shutter is fully closed the cranks also occupy the vertical positions, so that the crank-arm 19 will be held in firm rigid engagement with the locking-plate, thus preventing 55 the wind from blowing the shutter open in stormy weather.

My improved construction wholly dispenses with separate fastening or locking devices for 60 the shutter in its opened or closed positions, and the device is readily applicable to ordinary shutters and windows without change in the construction thereof. The employment of the loose connection between the eye-formed 65 ends of the rod, the bracket, and the crank-arm enables the device to be applied

to shutters which are hung by hinges of different styles and sizes.

It is evident that changes in the form and proportion of parts may be made by a skilled 70 mechanic without departing from the spirit or sacrificing the advantages of the invention.

Having thus described the invention, what I claim is—

1. The combination with a sash having a recess in its lower edge, of a journal-plate 75 fixed to the window-sill outside of the sash, a shaft journaled in said plate, extending through the recess in the sash and provided with the collar which is adapted to abut against the sash and close the recess therein, a spring seated against the journal-plate and the shaft-collar, a shutter-bracket, a crank-arm on the shaft, and a rod, substantially as 80 85 and for the purposes described.

2. In a shutter-worker, the combination of a journal-plate provided with a series of transverse apertures which extend entirely through said plate, an operating-shaft fitted loosely 90 in the journal-plate for axial and endwise movement therein, and provided with a collar, a crank-arm rigid with the shaft and provided with a locking-stud adapted to engage with the apertures of said plate, a shutter- 95 bracket, and a rod connected directly to the shutter-bracket and the crank-arm, substantially as described.

3. The combination with a sill and a sash having a recess in its lower edge, of a plate 100 fixed to the sill outside of the sash and provided with a journal-boss and a series of transverse apertures, a shaft fitted loosely in the sash-recess and boss of the plate and provided at an intermediate point of its length with a 105 collar arranged to bear against the sash and close the recess therein, a spring fitted on the shaft and seated against its collar and the boss of the journal-plate, a crank-arm rigidly attached to the outer end of the shaft and provided at its free end with an eye and at an intermediate point of its length with a locking-stud adapted to either of the apertures in said plate, a shutter-bracket provided 110 with an eye, and an eye-formed rod loosely 115 connected to the eyes of the shutter-bracket and the crank-arm, substantially as described.

4. In a shutter-worker, the combination of a shutter-bracket having a rounded eye, a journal and locking plate provided with a 120 bearing, a shaft fitted in said bearing for turning and sliding adjustment therein, a crank-arm attached to said shaft and having a locking-stud and a rounded eye, a spring seated against said shaft and the plate, and a connecting-rod provided at its ends with eyes 125 which are loosely connected with the eyes of said bracket and the arm, respectively, whereby the rod is directly attached to the bracket and crank-arm and the shutter may be opened 130 or closed and locked without auxiliary devices, substantially as described.

5. In a shutter-worker, the combination of a plate, a shaft journaled therein and provided at a point intermediate of its length with a collar adapted to close a recess in a 5 sash through which the shaft is adapted to pass, a shutter-bracket, and connections between the bracket and the shaft, substantially as described.

In testimony that I claim the foregoing as my own I have hereto affixed my signature in 10 the presence of two witnesses.

RANDOLPH N. MARTZ.
